POULTRY FEEDER AND WATERER

Francis W. Buckle, Glanford Township, Ontario,
Canada

Application November 30, 1936, Serial No. 113,494

3 Claims. (Cl. 119—73)

The invention relates to a feeder and waterer and more especially to a poultry feeding and watering device.

An object of the invention is the provision of a device of this character, wherein a support is afforded concentrically to a pan for containing feed or water and is possessed of sufficient strength to resist the load or pressure of the pan, the support being of novel construction and is carried by legs which with the support constitute a stand for the carrying of the pan.

A further object of the invention is the provision of a device of this character, which is simple in construction, thoroughly reliable and effective in operation, readily portable, comparatively light in weight yet strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

25 In the accompanying drawing:

Figure 1 is a side elevation partly in section of the device constructed in accordance with the invention.

Figure 2 is a top plan view with the pan removed.

Figure 3 is an enlarged fragmentary bottom plan view looking toward the top of the stand.

Figure 4 is a sectional view on the line 4—4 of Figure 3 looking in the direction of the arrows.

Figure 5 is a sectional view on the line 5—5 of Figure 3 looking in the direction of the arrows.

Similar reference characters indicate corresponding parts throughout the several views in the drawing.

Referring to the drawing in detail, the device constituting the present invention comprises a wheel shaped open top A involving what may be termed a rim 10 composed of a group or series 45 of wood sectors 11, these being disposed with their ends next to each other in abutting relation and such sectors are preferably wider at their intermediate portions than at their ends, being cut from wood planks through the use of a special pattern for economy in labor and avoiding undue waste of material in the procuring of the required number of sectors for the completing of the support on erecting the same. The sectors 11 when abutting each other end to 55 end afford a polygonal or otherwise shaped open

center to the top while underlying this top is a metal frame 12 made from strap iron which is welded or otherwise made secure to vertical legs 13 for supporting the wheel shaped top. These legs 13 are uniformly spaced from each other and their lower ends are adapted to rest upon a foundation or floor within an enclosure for poultry or the like. Welded or otherwise made secure to the lower ends of the said legs is a bottom iron hoop or band 14 thus holding these legs in 10 their uniformly spaced relation to each other. The legs 13 are made from strap iron.

At the center of the open center of the top A is in this instance a ring 15 although it may be otherwise shaped and has welded or otherwise 15 secured to the outer side thereof lateral or radially projected arms 16 which are joined together in pairs preferably by welding or otherwise and these pairs of arms are evenly spaced from each other and radiate toward the inner periphery of the rim 10. The outer end of one arm 16 of each pair is twisted at 17 to effect a horizontal terminal 18. The terminals 18 in their radial disposition are disposed at the under side of the rim 10 and are made secure in place by staples 25 19 which straddle said terminals and are driven into the rim 10. The other arm of each pair is provided with a downturned attaching ear 20 welded or otherwise secured to an adjacent leg 13 at the inner side thereof and at its upper 30 end, the frame 12 is disposed against the outer sides of the legs 13 and welded or otherwise secured thereto.

The pairs of arms 16 next to the ring 15 through the intermediate connecting portions 21 35 are welded or otherwise made fast to said ring 15.

Underlying the top A at those joints between the sectors 11 of the rim are saddling strap iron plates 22, these are secured in place by 40 staples 23 straddling said plates and driven into the rim 10.

The plates 22 are formed with downwardly struck loop portions 24 affording seats for the frame 12 45

The legs 13 have secured thereto diagonal braces 25 which are formed with upper protruded beveled ends 26 welded or otherwise made secure to the arms 16 so that these ends 26 project slightly above the plane of the arms for 50 effecting abutments for a removable pan 27 whereby the latter will be held seated upon the said arms 16 at the center of the center opening in the top A. This pan 27 is adapted to accommodate water or feed for poultry. It may be 55

found desirable to fit around the ring 15 a lamp house 28 for an oil burning lamp 29 and the wall of this lamp house 28 is preferably welded or otherwise secured to the ring and is of a kind to eliminate the necessity of a shade for the burner of the lamp. Thus the contents of the pan 27 can be readily heated by the use of the lamp should it be found desirable.

In the use of the device the poultry when seeking feed or water will light onto the top A and when perched thereon can have convenient access to the pan 27 for feeding or watering purposes.

By reason of the construction of the device a support is afforded concentric to a pan and is possessed of sufficient strength to resist the load or pressure of the said pan and its contents.

What is claimed is:

1. A device of the character described comprising a sectional rim forming a support having a center opening, a frame beneath the rim, vertical legs secured to the frame in spaced relation to each other, radial arms having flattened outer ends disposed at the open center of said rim, the flattened ends being in underlying relation to the rim, certain of the flat ends being turned to provide depending ears secured to the legs, means uniting the arms together at the open center of the rim in their radially disposed relation to each other, a hoop fixed to the legs near their lower ends, a pan removably resting upon the arms and held within the rim, and means connected with the arms to form abutments for the pan and holding the same centered with respect to the open center of said rim.

2. A device of the character described comprising a sectional rim forming a support having a center opening, a frame beneath the rim, vertical legs secured to the frame in spaced relation

to each other, radial arms having flattened outer ends disposed at the open center of said rim, the flattened ends being in underlying relation to the rim, certain of the flat ends being turned to provide depending ears secured to the legs, means uniting the arms together at the open center of the rim in their radially disposed relation to each other, a hoop fixed to the legs near their lower ends, a pan removably resting upon the arms and held within the rim, and means connected with the arms to form abutments for the pan and holding the same centered with respect to the open center of said rim.

3. A device of the character described comprising a sectional rim forming a support having a center opening, a frame beneath the rim, vertical legs secured to the frame in spaced relation to each other, radial arms having flattened outer ends disposed at the open center of said rim, the flattened ends being in underlying relation to the rim, certain of the flat ends being turned to provide depending ears secured to the legs, means uniting the arms together at the open center of the rim in their radially disposed relation to each other, a hoop fixed to the legs near their lower ends, a pan removably resting upon the arms and held within the rim, and means connected with the arms to form abutments for the pan and holding the same centered with respect to the open center of said rim, plates straddling certain of the joints between the sections of the rim and secured to said sections, and loops formed in the said plates and accommodating the frame for securing the latter to the rim.
